CLAIM

The ornamental design for a timber fencing with guardrail, as shown.

DESCRIPTION

FIG. 1 is an elevational view of a pair of panels of timber fencing with guardrail showing my new design;

FIG. 2 is a top plan view thereof;

FIG. 3 is a side elevational view thereof from the left of FIG. 2;

FIG. 4 is an elevational view of the opposite side thereof;

FIG. 5 is a view similar to FIG. 1, showing a modified form thereof; and

FIG. 6 is a view similar to FIG. 4, showing the embodiment of FIG. 5.

I am the owner of U.S. Pat. No. D-257,177, which issued Sept. 30, 1980.

FIG. 1.

FIG. 4.

FIG.2.

FIG.3.

FIG. 5.

FIG. 6.
